UNITED STATES PATENT OFFICE.

FREDERICK B. RYAN, OF SHORT HILLS, NEW JERSEY, AND CARL F. DOSCHER, OF WHITE PLAINS, NEW YORK, ASSIGNORS TO THOMPSON-BARLOW COMPANY, INC., A CORPORATION OF NEW YORK.

SCALP-MASSAGE APPARATUS.

Application filed September 24, 1921. Serial No. 502,995.

To all whom it may concern:

Be it known that we, FREDERICK B. RYAN and CARL F. DOSCHER, citizens of the United States, and residents, respectively, of Short Hills, county of Essex, and State of New Jersey, and White Plains, New York, have invented certain new and useful Improvements in Scalp-Massage Apparatus, of which the following is a specification.

10. This invention relates to improvements in scalp massage apparatus.

One of the objects of this invention is to produce a massage device for the scalp which will simultaneously enable the massage of 15 the entire scalp including those portions thereof which cover the frontal, parietal, temporal and occipital bones of the human cranium.

Another object of our invention is to produce 20 a massage device which will initially contact with a relatively large area of the scalp and preferably covers a major portion thereof leaving a minor uncovered portion for movement so that a relatively slight 25 movement of the device will massage the skin-covering of the frontal, parietal, temporal and occipital portions of the cranium at the same time.

Another object of our invention is to produce 30 a scalp-massage device which will be in the form of a spherical or spheroidal segment and so shaped and proportioned in relation to the human cranium that the latter will guide the movement of the same 35 backwardly and forwardly in an arcuate path and such movement will cause the simultaneous massaging of the skin covering the frontal, parietal, temporal and occipital portions of the cranium without contact with the ears of the person massaged.

In the preferred embodiment of our invention, we provide a massage helmet comprising a shell of rubber or similar elastic material embodying substantially a convex 45 or spherical parietal portion having an operating handle attached thereto and adapted to initially cover the parietal portion of the cranium, a relatively short forwardly-projecting frontal portion of substantially 50 similar shape merging with said parietal portion, temple portions at opposite sides merging with said frontal and cap portions and a rear or occipital portion also of similar convexity projecting downwardly at the

opposite side of said portion and so proportioned and arranged in relation to the cap and temple portions as to leave ear cut-out portions to prevent interference or contact with the ear during movement, said shell preferably having distributed over the inner concave surface thereof a series of massage projections and preferably a series of isolated elastic rubber prongs or fingers adapted when the helmet is in place on the head to contact with the scalp or skin covering of the cranium and when the helmet is moved in an arcuate path about the cranium to contact with and massage substantially the entire scalp or skin covering of the frontal, parietal, temporal and occipital portions of the cranium.

With these and other objects in view, the invention comprises the combination of members and arrangements of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a perspective view of a massage helmet embodying our invention;

Fig. 2 is a side view of a human head having the helmet applied thereto, said helmet being shown in section.

Referring now to these drawings, 1 indicates a helmet which preferably comprises a soft or elastic rubber shell and is, as shown in Fig. 2, adapted to cover and contact with a major portion of the human scalp but to leave uncovered a minor portion of such scalp so as to enable a massage movement back and forth to effectively massage the entire scalp.

As illustrated, the said helmet is in the form of a spheroidal segment so as to conform in shape with the human cranium and to enable the guiding by such human cranium of the shell or helmet in its massaging movement. The said shell 1 is composed of a spheroidal parietal portion 1^a which is substantially centrally disposed and has an operating handle 2 attached thereto, a relatively short and forwardly projecting frontal portion of substantially similar spheroidal shape merging with said parietal portion, temple portions 1^c projecting

laterally at opposite sides of said frontal portion 1^b and an occipital portion 1^d also of similar spheroidal shape and projecting rearwardly from said parietal portion, said 5 temple and occipital portions being so proportioned and arranged in relation to the parietal portion as to leave ear cut-out portions 1^e and substantially straight occipital edge portions 1^f whereby interference or 10 contact with the ear during movement of the device to and fro in contact with the scalp is prevented. The helmet or shell is provided on its inner surface with a series of massage projections which, as shown, are 15 preferably in the form of a series of isolated elastic rubber prongs 3 distributed over the entire inner surface of the various portions of the shell, so that when the shell is moved in a backwardly and forwardly massaging 20 movement over the scalp these prongs or fingers will contact with all portions of the scalp and give a thorough massage thereto. The distance and arrangement of these prongs are preferably so proportioned as 25 to cause each prong upon a massaging movement to cover a given scalp area so that the combined massaging contact of the entire series will during the movement of the device contact with and massage substantially 30 the entire scalp or the skin covering of the parietal, frontal, temporal and occipital portions of the human cranium.

The operation of the device will be apparent from the foregoing description.

35 Having described our invention, we claim:—

1. In scalp massage apparatus, a massage helmet comprising a shell of elastic rubber conforming in shape with a major portion 40 of the scalp of the human cranium, and comprising a substantially spheroidal parietal portion having an operating handle attached to the outer side thereof, a relatively short forwardly projecting frontal portion 45 of substantially similar spheroidal shape merging with said parietal portion, a temple portion extending at opposite sides of said frontal portion and an occipital portion extending rearwardly from said parietal portion 50 also of substantially similar shape, said rubber shell having distributed over its inner surface a series of massage projections adapted to contact with and massage substantially the entire scalp upon a relatively 55 slight movement of the said shell.

2. In scalp massage apparatus, a massage helmet comprising a shell of elastic rubber conforming in shape with a major portion of the scalp of the human cranium, and comprising a substantially spheroidal parietal portion having an operating handle attached to the outer side thereof, a relatively short forwardly projecting frontal portion of substantially similar spheroidal shape merging with said parietal portion, a temple portion extending at opposite sides of said frontal portion and an occipital portion extending rearwardly from said parietal portion also of substantially similar shape, said rubber shell having distributed over its inner 60 surface a series of massage projections each comprising isolated elastic rubber prongs distributed on the inner surface of said shell and adapted to contact with and massage substantially the entire scalp upon a relatively slight movement of the said shell.

3. In scalp massage apparatus, a massage helmet comprising a shell of elastic rubber conforming in shape with a major portion of the scalp of the human cranium, and comprising a substantially spheroidal parietal portion having an operating handle attached to the outer side thereof, a relatively short forwardly projecting frontal portion of substantially similar spheroidal shape 65 merging with said parietal portion, a temple portion extending at opposite sides of said frontal portion and an occipital portion extending rearwardly from said parietal portion also of substantially similar shape, said 70 temple, parietal and occipital portions being proportioned and arranged to provide cut-out ear portions intermediate the temple and occipital portions, said shell also having a series of massage projections on 75 its inner surface whereby the helmet will initially contact with a major portion of the human scalp and may in the operation of massaging the entire scalp be moved in a relatively short arcuate path over the 80 frontal, parietal, temporal and occipital portions without contact with the ear.

In witness whereof, we have signed our names to the foregoing specification in the presence of two subscribing witnesses.

FREDERICK B. RYAN.
CARL F. DOSCHER.
